BOTTLE HANDLER HAVING PIVOTED JAWS

Warren H. Mercer, Anaheim, Calif., assignor of fifty per cent to Israel H. Harris and Virginia V. Harris, Huntington Park, Calif.

Application April 29, 1949, Serial No. 90,487

8 Claims. (Cl. 294—31)

1

This invention relates to novel and useful improvements in bottle holders.

An object of this invention is to support the neck of a bottle or other container by means of a frame which has an open end for receiving the neck of a container, the bottle neck being insertable in the open end and clamped in place by means of a number of jaws which are pivoted at their outer ends or the ends which would be closest to the body of the container and which move inwardly at the tops thereof adjacent the bottle cap.

Another object of this invention is to automatically lock the jaws in the bottle engaging or closed position by an improved cam arrangement whereby the jaws may be swung pivotally in an outward direction with respect to the neck of a bottle upon release of the cam-operated locking device, which locking device is adapted to be operated by the same hand of an individual which supports the entire frame.

Another object of this invention is to oppose the operation of the locking means by a resilient member and also oppose the operation of the jaws by other resilient members which react on the jaws and another portion of the frame.

Ancillary objects and features of novelty will become apparent to those skilled in the art, in following the description of the preferred form of the invention, illustrated in the accompanying drawings, wherein:

Figure 1 is an elevational view of the invention, portions being broken away in section to illustrate detail of construction;

Figure 2 is a view similar to that shown in Figure 1, showing a second operative position of the parts;

Figure 3 is a fragmentary elevational view showing the handles which are used in conjunction with and form a part of the invention;

Figure 4 is a transverse sectional view taken on the line 4—4 of Figure 1 and in the direction of the arrows;

Figure 5 is a longitudinal sectional view of the preferred form of the invention;

Figure 6 is a perspective view of one of the jaws used in conjunction with the invention;

Figure 7 is a transverse view taken substantially on the line 7—7 of Figure 5 and in the direction of the arrows, and;

Figure 8 is a bottom plan view of the device shown in Figure 1.

This invention is adapted for use in lifting and holding containers of various types, particularly those having reduced necks such as large jars,

2

bottles and the like. The operation of the invention is such that by merely pulling one handle with respect to the other by the same hand, the bottle neck may be inserted in a throat portion. By releasing the handle and allowing it to return by means of a spring operation, the bottle neck becomes firmly clamped in the throat for holding and lifting. In order to release the bottle it is only necessary to raise one handle with respect to the other against the operation of the said spring, this in turn operating to release a number of pivoted jaws so that the bottle neck may simply slide from the said throat.

The container lifter and holder frame 10 is composed of any suitable material preferably primarily metallic. The said frame consists of various parts including a block 12 which has an inner sleeve 14 and an outer sleeve 16 over the said inner sleeve and a cap plate 18 disposed at the top of the block. The said block 12 is appreciably shorter than both sleeves and since it is disposed therein, the lower part of the sleeve is open thereby forming a chamber 20.

A passage 22 extends centrally through the block 12 and also through the cover plate 18. Disposed in this passage for reciprocating movement is a rod 24 which has a handle 26 carried by one end thereof by any suitable means such as a threaded, riveted, or welded connection. The handle 26 seats on the cover plate and is normally pressed thereagainst by the action of a spring 28 which reacts on the cover plate and the rod 24, to which one end of the spring is attached. Hence, upon lifting the handle 26 the rod 24 will be slidably actuated thereby compressing the spring and thereby opposing the operation of the rod always tending to return it until the handle is at rest on the plate 18.

A guide plate 30 is disposed within the chamber 20 and has a central aperture through which the rod passes.

In order that a bottle or other type of container may be lifted, held and released by one hand of a person, a second handle 32 is carried by the outer sleeve 16 and is held in place by a suitable means such as spot welding, or by the use of screws, rivets or the like. The said handles 26 and 32 are in nested relationship with each other thereby rendering it convenient to operate the handle 26 and to actually hold the entire frame 10 by one hand.

A ring or retainer 34 is maintained at a spaced position with respect to the block 12 by a specific means provided for this purpose. The said specific means includes a number of arms 36

which are fixed at one end to the sleeves and which are fixed at the other end to the retainer 32. The said retainer 32 is appreciably larger in diameter than the sleeves and since the arms 34 are substantially straight, a flared throat portion is supplied. Strengthening members 36 are fixed to the outer surfaces of each of the arms 34 in order to have a rigid structure at this point. A number of jaws, one of which is shown in Figure 6, are pivoted at their outer ends and specifically to the retainer 32. Accordingly, the jaws are fixed at their outer ends with respect to having their pivot axes at the retainer 32 but are allowed arcuate travel at the other ends thereof which in this instance will be the inner ends with respect to the throat or bottle receiving opening.

The jaws consist of strips 38 having bights 40 at the lower ends thereof which are disposed around the retainer 32. Small rings 42 which form stops are carried by the retainer thereby preventing movement of the jaws around the retainer, considering this movement as circumferential with respect to the retainer. An inwardly bent portion 44 is provided in each strip 38 which supports a cam 46 having a substantially flat and straight extension 48 thereon. The inner surface of a block 50 which is carried by each strip 38 is undulated as seen at Figure 2 in order to form a gripping surface for the neck portion of bottle. It is noted that the undulations are substantially similar in amplitude but each half wave length decreases in size from the outer undulation to the inner undulation. Thus, a number of cams of unequal size form the inner surfaces of the jaws.

An operating plate 54 is disposed in the chamber 20 and is carried by the inner end of the rod 24. It is maintained in place by any suitable means such as the nut 57 which is disposed on the threaded end portion of the shank 24 engaging the said plate 54. The plate in turn may have a threaded aperture so it too will be threaded on the shank 24. A number of apertures (Figure 7) 56 are provided in the operating plate 54, one aperture being provided to accommodate each cam 46 and each extension 48 on the jaws.

As disclosed in Figure 5 the cams 46 are disposed in the apertures 56 when the plunger 24 is in the full down position. Hence, substantial pivotal movement of the jaws is precluded. Springs 58 are attached to each strip and are held in place by means of the strengthening strips 60. The ends of the springs 58 are disposed in the chamber 20 and press against the inner surface of the outer cylinder or sleeve 16. Accordingly, the springs 58 which are of light resiliency and weight gently urge the jaws inwardly into clamping contact with a bottle neck.

In operation the handle 26 is lifted thereby lifting the operating plate 54. Hence, since the cam 46 on each jaw is passed (thick portion thereof) the jaws are free to move pivotally a limited amount. A bottle or other type of container neck may then be easily inserted in the throat or bottle receiving opening. The usual operation will be simply placing the container lifter and holder on the neck of the bottle. Then, by releasing the handle 26, the spring 28 pulls the operating plate downwardly so that the apertures 56 pass over the thick portions of the cams thereby maintaining them substantially immovable with respect to pivotal movement. The conventional rings 68 around the neck of the container 70 are disposed between the undulations

thereby precluding the possibility of the bottle falling out. To release the container 70 from the jaws it is only necessary to repeat this operation.

5 Means for preventing the tendency of rotation of the rod 24 is provided. Various means may be provided for this purpose however, due to the passage structure 22, it has been found desirable to use a pair of stay rods 72 which are carried 10 by the handle 26 and which pass through suitable passages in the block 12. These rods are attached at one end to the handle 26 and at the other end to the operating plate 30, as disclosed in Figure 2.

15 While there has been described and shown but the preferred form of the invention, it is apparent that variations may be made without departing from the spirit thereof.

Having described the invention, what is 20 claimed as new is:

1. A container lifter and holder comprising a frame which includes a block having a passage therethrough, a retainer, means fixing said retainer at a position spaced from said block forming a throat for receiving a part of a container, jaws pivoted at their ends to said retainer, and means extending through said passage for releasably locking said jaws in a predetermined position with respect to each other, said locking 25 means including a rod, an operating member secured to said rod and having apertures therein, and cams carried by said jaws and disposed in said apertures imparting pivotal movement to said jaws when said member is motivated.

30 2. A container lifter and holder comprising a frame which includes a block having a passage therethrough, a retainer, means fixing said retainer at a position spaced from said block forming a throat for receiving a part of a container, 35 jaws pivoted at their ends to said retainer, and means extending through said passage for releasably locking said jaws in a predetermined position with respect to each other, said locking means including a rod, an operating member secured to said rod and having apertures therein, 40 cams carried by said jaws and disposed in said apertures imparting pivotal movement to said jaws when said member is motivated, and a spring 45 reacting on said operating member and said block 50 opposing the operation of said rod.

3. A container lifter and holder comprising a frame which includes a block having a passage therethrough, a retainer, means fixing said retainer at a position spaced from said block forming a throat for receiving a part of a container, 55 jaws pivoted at their ends to said retainer, and means extending through said passage for releasably locking said jaws in a predetermined position with respect to each other, said locking means including a rod, an operating member secured to said rod and having apertures therein, 60 cams carried by said jaws and disposed in said apertures imparting pivotal movement to said jaws when said member is motivated, a spring 65 reacting on said operating member and said block 70 opposing the operation of said rod, and handles secured to said rod and said block disposed adjacent each other.

4. A container lifter and holder comprising a 75 frame having an opening adapted to receive a part of a container, jaws pivoted to the outer end of said frame and movable in said opening, and means carried by said frame for locking said jaws in a container holding position including a rod movably carried by said frame, an operating

member operatively connected with said rod and having apertures therein, and cams secured to said jaws and disposed in said apertures when said operating member is actuated to pivotally operate said jaws.

5. A container lifter and holder comprising a frame having an opening adapted to receive a part of a container, jaws pivoted to the outer end of said frame and movable in said opening, and means carried by said frame for locking said jaws in a container holding position including a rod movably carried by said frame, an operating member operatively connected with said rod and having apertures therein, cams secured to said jaws and disposed in said apertures when said operating member is actuated to pivotally operate said jaws, undulations on the inner surfaces of said jaws, and a spring carried by said frame opposing the operation of said operating member.

6. A container lifter and holder comprising a frame having an opening adapted to receive a part of a container, jaws pivoted to the outer end of said frame and movable in said opening, and means carried by said frame for locking said jaws in a container holding position including a rod movably carried by said frame, an operating member operatively connected with said rod and having apertures therein, cams secured to said jaws and disposed in said apertures when said operating member is actuated to pivotally operate said jaws, and handles carried by said rod and said frame respectively in nested relationship so that the rod

handle may be operated while holding the frame and by the same hand.

7. The combination of claim 6 and a spring opposing the operation of said operating member and retaining said member in the jaw closing position.

8. A container lifter and holder comprising a frame having an opening adapted to receive a part of a container, jaws pivoted to the outer end of said frame and movable in said opening, means carried by said frame for locking said jaws in a container holding position including a rod movably carried by said frame, an operating member operatively connected with said rod and having apertures therein, cams secured to said jaws and disposed in said apertures when said operating member is actuated to pivotally operate said jaws, and resilient means secured to each of said jaws and reacting on said frame opposing pivotal movement of said jaws.
